ADJUSTABLE BACK LOUNGE CHAIR

Chester J. Barecki and Robert T. Knapp, Grand Rapids, Mich., assignors to American Seating Company, Grand Rapids, Mich., a corporation of New Jersey
Filed Nov. 12, 1964, Ser. No. 410,358
2 Claims. (Cl. 297—369)

This invention relates to an adjustable back lounge chair, and more particularly to a lounge chair for patients and invalids in hospitals, nursing homes, doctors' offices, etc.

An object of the invention is to provide a lounge chair which may be readily adjusted to place the back of the chair at varying angles whereby the patient may be seated in a normal position or in a position for a head support, or the back may be adjusted for lumbar support. A further object is to provide a lounge chair wherein the back may be adjusted to a plurality of positions, including an erect position and at least four additional positions as desired. Yet another object is to provide in a tubular chair frame means actuated by a control lever along one side of the seat for readily adjusting the angle of the chair back. Other specific objects and advantages will appear as the specification proceeds.

The invention is shown in an illustrative embodiment by the accompanying drawings, in which:

FIGURE 1 is a perspective view of a lounge chair embodying our invention; FIG. 2, a side view in elevation, adjusted positions of the back of the chair being shown in dotted lines; FIG. 3, a rear view in elevation; FIG. 4, a broken top plan view, a portion of the cushions being removed to show the chair structure; FIG. 5, an enlarged detail and part sectional view showing the pivot guide and locking mechanism utilized for controlling the position of the chair back, the back being shown in normal position; FIG. 6, a view similar to FIG. 5 but showing the adjusting mechanism being moved for the selection of a second position; FIG. 7, a view similar to FIG. 6 but showing the adjustment completed; FIG. 8, a view similar to FIG. 7 but showing the locking mechanism adjusted for supporting the back in a further and more rearwardly-inclined position; FIG. 9, a detail sectional view, the section being taken as indicated at line 9—9 of FIG. 5; and FIG. 10, a detail sectional view, the section being taken as indicated at line 10—10 of FIG. 5.

In the illustration given, 10 designates a tubular seat frame supported in a generally horizontal position by legs 11. The legs 11 on each side of the frame are welded to the tubular frame 10 but are also extended upwardly to support a cushion armrest 12 on each side of the chair. Secured to the U-shaped frame 10 is a bottom pan 13 for supporting a cushion seat 14. Also welded to each side rail of the seat frame 10 are upwardly-extending pivot standards 15.

The back frame 16 is provided by a tubular U-shaped member, and the member 16 is connected at its lower ends by a crosspiece 17. A back sheet 18 is connected to the crossbar 17 and to the upper rail of frame 16 to provide a support for the back cushion 19.

The back frame 16 is pivotally mounted upon the standards 15 by pivot pins 20.

Means for adjusting the position of the back 16 will now be described. As shown best in FIG. 3, one leg of the back frame 16 is extended downwardly and flattened at 21 and lying adjacent the tubular seat rail 10a. The tubular member 10a is provided on its inner side with a slot 22 adapted to receive a connector pin 23 which extends into the flattened portion 21 of the back 16.

As shown best in FIGS. 5—10, the pin 23 extending through the elongated slot 22 engages a guide head 24 which forms part of a pivot guide within the tubular

2

member 10a. Extending forwardly of the head 24 is a stem 25 which is secured at its forward end to an elongated ratchet bar 26 having downwardly-extending spaced teeth 27. A spring 28 engages at its rear the head 24, and at its forward end is confined by inwardly-extending screws 29.

A lever 30 extends upwardly along the side of the cushion 14 and is secured to an arm 31 which extends forwardly and which carries locking teeth 32. The tubular member 10a is cut away at 33 to permit the teeth 32 to extend upwardly and engage the teeth 27 of the ratchet 26. The arm 31 is connected to a U-shaped member having upwardly-extending wings 34 enclosing the sides of the tube 10a, and a pivot pin 35 supports the arm upon the tube 10a. A rearwardly-extending portion of the arm 31 is provided with a pin 36 receiving a spring 37, and the upper end of the spring is anchored within tube 10a by a pin 38.

To prevent rotation of the ratchet member 26, we provide a stud or screw 39 which engages a longitudinal slot 40 in the member 26.

Operation

In the operation of the structure, the patient may be seated in the lounge chair in the normal position illustrated in solid lines in FIGS. 1 and 2, but by manipulating the pivot control mechanism, the back may be moved to the various positions shown in dotted lines in FIG. 2. To effect the movement from normal position to a rearwardly-inclined back position, the patient or other user may raise the lever 30 so as to depress the bar 31, as shown in FIG. 6, and the patient may then move the back against the force of spring 28 to a desired inclined position and then, upon releasing the lever 30, spring 37 urges the teeth 32 upwardly into engagement with the teeth 27 of ratchet 26. Adjustment to at least five positions is provided with the ratchet means shown, but it will be understood that additional teeth may be provided for further adjustments if desired. The cylindrical head member 24 and the cylindrical ratchet member 26 provide stabilized supports for the pivot control whereby movement of the back is accomplished smoothly and evenly, and the patient or occupant is able to make the adjustments with a minimum of effort.

While in the foregoing specification we have shown a specific embodiment in considerable detail for the purpose of illustrating our invention, it will be understood that such detail or details may be varied widely by those skilled in the art without departing from the spirit of our invention.

We claim:

1. In a chair, a horizontal tubular seat frame, a cushion carried by said frame, legs supporting said frame and extending thereabove, armrests carried by said legs above said cushion, pivot standards mounted on said seat frame and extending upwardly therefrom, a back frame pivotally mounted on said standards, a cushion carried by said back frame, one side of said back frame being extended downwardly adjacent a tubular side member of said seat frame, said tubular member being provided on its inner side with a longitudinal slot, a pivot guide slidably mounted in said tubular member and provided at its rear end with a head and at its forward end with a cylindrical ratchet having its lower surface cut away to form downwardly-extending teeth, a pin extending through said slot and connecting said pivot guide head and said extended portion of said back frame, a spring within said tubular member engaging said head, pins extending through said tubular member and restricting forward movement of said spring, a pin extending through said tubular member and engaging a longitudinal slot within said ratchet member, a lever pivotally mounted on said

tubular member and having a rearwardly-extending arm equipped with upwardly-extending tooth means, said tubular member being cut away to allow said tooth means to engage selectively said ratchet teeth for latching said ratchet in a plurality of longitudinal positions, and spring means normally urging said arm upwardly.

2. In a chair, a horizontal tubular seat frame, a seat carried by said frame, legs supporting said frame and extending thereabove, pivot standards mounted on said seat frame and extending upwardly therefrom, a chair back pivotally mounted on said standards, one side of said chair back being extended downwardly adjacent a tubular side member of said seat frame, said tubular member being provided on its inner side with a longitudinal slot, a pivot guide slidably mounted in said tubular member and provided at its rear end with a head and at its forward end with a cylindrical ratchet having its lower surface cut away to form downwardly-extending teeth, a pin extending through said slot and connecting said pivot guide head and said extended portion of said chair back, a spring within said tubular member engaging said head, pins extending through said tubular member and restrict-

5 ing forward movement of said spring, a pin extending through said tubular member and engaging a longitudinal slot in the upper portion of said ratchet member, a lever pivotally mounted on said tubular member and provided with a rearwardly-extending arm equipped with upwardly-extending tooth means, said tubular member being cut away to allow said tooth means to engage selectively said ratchet teeth for latching said ratchet in a plurality of longitudinal positions, and spring means normally urging said arm upwardly.
